(57) **CLAIM**

The ornamental design for a “beverage pitcher with an integral ice reservoir,” as shown and described.

DESCRIPTION

FIG. 1 is a right side view of the “beverage pitcher with an integral ice reservoir” showing my new design, the left side being a mirror image thereof:

FIG. 2 is a perspective view of the beverage pitcher with an integral ice reservoir thereof:

FIG. 3 is a top view of the beverage pitcher with an integral ice reservoir thereof:

FIG. 4 is a bottom view of the beverage pitcher with an integral ice reservoir thereof:

FIG. 5 is a front view of the beverage pitcher with an integral ice reservoir thereof; and,

FIG. 6 is a rear view of the beverage pitcher with an integral ice reservoir.
